(57) **CLAIM**

The ornamental design for a translucent tool card, as shown and described.

DESCRIPTION

FIG. 1 is a top perspective view from the front of the translucent tool card of the present invention;

FIG. 2 is a top view thereof;

FIG. 3 is a bottom view thereof;

FIG. 4 is a right side view thereof;

FIG. 5 is a left side view thereof;

FIG. 6 is a front end view thereof;

FIG. 7 is a rear end view thereof;

FIG. 8 is a top view of a second embodiment of the translucent tool card of the present invention;

FIG. 9 is a bottom view thereof;

FIG. 10 is a left side view thereof;

FIG. 11 is rear end view thereof, all other views thereof being identical to FIGS. 4, and 6;

FIG. 12 is a top view of a third embodiment of the translucent tool card of the present invention; and,

FIG. 13 is a left side view thereof, all other views thereof being identical to FIGS. 3, 4, 6, and 7.

The broken lines are for illustrative purpose only and forms no part of the claimed design.
